UNITED STATES PATENT OFFICE.

AUGUSTINE RIDENOUR AYERS, OF CHICAGO, ILLINOIS, ASSIGNOR TO WALTER P. MURPHY, OF CHICAGO, ILLINOIS.

DEVICE FOR CHECKING THE TENDENCY OF TRAIN-PIPES TO SHIFT LONGITUDINALLY.

1,211,039

Specification of Letters Patent.

Patented Jan. 2, 1917.

Application filed March 20, 1913. Serial No. 755,612.

To all whom it may concern:

Be it known that I, AUGUSTINE R. AYERS, a citizen of the United States, residing at Chicago, in the county of Cook and State 5 of Illinois, have invented certain new and useful Improvements in Devices for Checking the Tendency of Train-Pipes to Shift Longitudinally, of which the following is a specification.

My invention relates to the train pipes forming part of the air brake or heating systems of railway cars, and the principal 10 object of the invention is to provide an effective and inexpensive means for preventing said train pipes from shifting longitudinally.

The invention has reference, more particularly, to air train pipes, for reasons which will be apparent from the following description 15 of the invention, but the improvements constituting the invention might be used, under certain circumstances, in connection with the steam line.

The air train pipe of a railway car is ordinarily suspended under the flooring of 20 the car by means of the hangers which take a frictional grip upon the pipe. The reservoir in which is stored compressed air for operating the air brakes, for example, is 25 connected with the train pipe by means of a branch pipe. If the train pipe shifts longitudinally in its hangers the branch pipe is likely to be fractured or its connections with the main pipe or the reservoir are likely to 30 be broken or otherwise disturbed. The train pipe has a tendency to shift longitudinally for several reasons. In the first place, when the train starts and stops, and particularly 35 when it makes a short stop, the inertia of the pipe will tend to shift it. In the second 40 place, the train pipe may be pulled through the hangers one way or another when the car is uncoupled from the train. The train pipe couplers now ordinarily used 45 are of the gravity type which open automatically when the coupling hose are tautened. This feature of the coupling, which was originally intended merely to 50 prevent the rupture of the hose in case the trainmen forgot to uncouple the train pipe connections when breaking up the train, has led trainmen to save time and trouble by discontinuing the practice of uncoupling the train pipe couplers. Very frequently they 55 simply uncouple the car couplings leaving

the train line couplings to open automatically. This, of course, puts a considerable stress on the train pipes, tending to shift the same in the hangers. Similar stresses are exerted when the train rounds sharp or reverse curves and this is particularly the case when stiff, heavy hose, which are rapidly becoming common, are employed.

My invention provides a very simple and inexpensive device for preventing the train 60 pipe from shifting under these or other similar conditions.

A further object of the invention is to provide a device of this sort which may also serve as a support or hanger for the 65 pipe.

The invention has for further objects such other novel and improved devices, arrangements and constructions relating to train pipes as are shown in the accompanying 70 drawings and will be hereinafter described and claimed.

The invention is illustrated, in certain preferred embodiments, in the accompanying 75 drawings, wherein—

Figure 1 is a plan view of a portion of the under frame and piping of a railway car illustrating the preferred embodiment of my invention; Fig. 2, a sectional view taken on line 2—2 of Fig. 1, looking in the direction 80 of the arrows; Fig. 3, a view, in perspective, of the bracket forming a part of the train pipe supporting device shown in Figs. 1 and 2; Figs. 4, 5 and 6 are detail sectional views taken on lines 4—4, 5—5 and 6—6, 85 respectively, of Fig. 1, and Figs. 7 and 8, a side and end elevation, respectively, of a modified construction.

Like characters of reference designate 90 like parts in the several figures of the drawings.

Referring first to Figs. 1 to 6, inclusive, 95 designates the longitudinal sills of the car, 26 one of the end sills and 27 the cross ties. The train pipe, as usual, is made up of 100 a number of sections of pipe. In the arrangement shown in the drawings, the ends of the train pipe sections 28, 29, are secured in the opposite ends of a coupling element 30 which connects the branch pipe 31 with the train pipe, the branch pipe 31 leading to the air reservoir 32. The coupling element 30 is ordinarily provided with a strainer 33.

Referring now to Figs. 1 to 5, inclusive, 110 34 designates a bracket secured to one of the

longitudinal sills 25 of the car by means, for example, of the bolts 35. The bracket is provided with the projecting arms 36 which are designed to extend under the train pipe sections 28, 29. The arms 36 are spaced apart so that the coupling element 30 may fit in between them. Preferably straps or plates 37 are employed which extend over the pipe sections 28, 29 close to the coupling element 30 and are secured to the arms 36 by the bolts 38. It will be seen that this arrangement provides abutments for the opposite ends of the coupling member 30, which abutments absolutely prevent any longitudinal movement of the train pipe. The device also serves the purpose of a hanger or support for the pipe. It is obvious that if necessary devices of similar character might be used at other points along the train pipe so as to minimize the breakage of the pipes at the point of coupling. At the right hand side of Figs. 1 and 2 and in Fig. 6 I have shown a device of this character used as a hanger for the extremity of the train pipe. The train pipe section 39 is connected by a coupling 40 with a short pipe section 41 which forms a part of or is suitably connected with the angle cock 42. The bracket 43, which is bolted to one of the sills 25, is provided with projecting arms 44 which support the pipe sections 39, 41 and lie close against the opposite ends of the coupling 40. The angle cock preferably abuts the outer one of the two arms 44. The advantage of this arrangement of the angle cock is that it minimizes the danger of having the end of the train pipe and the angle cock broken off by the diagonal strains exerted on the pipe through the angle cock and its hose.

In Figs. 7 and 8 I have shown a modified construction. 45 designates a bracket secured to the sill 46, and 47 forked elements secured to the bracket by the bolts 48. Each fork extends over one of the pipe sections 49 or 50 and stands close up against the coupling element 51 which connects said sections together.

While I preferably arrange the device of my invention so as to take advantage of the projections or shoulders provided by one of the coupling elements commonly used for connecting together the pipe sections mak-

ing up the train pipe, it will be obvious that, for preventing the shifting movement of the pipes, the device might be used with train pipes differently constituted so long as shoulders or projections are provided capable of being engaged so as to hold the train pipe from longitudinal movement against the stresses to which the pipe is subjected under service conditions. It will also be obvious that the form and construction of my device might be modified without departure from my invention.

65

I claim:

1. In a device for supporting and preventing the longitudinal shift, in either direction, of a horizontally arranged train pipe, the combination with a plurality of aligned pipe sections, of a coupling member having an external diameter greater than that of the said train pipe interposed between said pipe sections and engaging the extremities thereof, means for rigidly securing said pipe sections to a car comprising a forked member adapted to be secured to the underframe of the car, the forked portions of said forked member extending under said pipe sections near their extremities and abutting against the opposite ends of said coupling member.

2. In a device for supporting and preventing the longitudinal shift, in either direction, of a horizontally arranged train pipe, the combination with a plurality of aligned pipe sections, of a coupling member having an external diameter greater than that of the said train pipe interposed between said pipe sections and engaging the extremities thereof, means for rigidly securing said pipe sections to a car comprising a forked member adapted to be secured to the underframe of the car, the forked portions of said forked member extending under said pipe sections near their extremities and abutting against the opposite ends of said coupling member, and clamping members fitted over said pipe sections and secured to said forked member.

AUGUSTINE RIDENOUR AYERS.
